UNITED STATES PATENT OFFICE.

JOSEPH PEYSER, OF MOUNT VERNON, NEW YORK, ASSIGNOR, BY MESNE ASSIGNMENTS, TO EMERGENCY UMBRELLA CORPORATION, OF NEW YORK, N. Y., A CORPORATION OF NEW YORK.

UMBRELLA OR PARASOL.

1,199,413.

Specification of Letters Patent. Patented Sept. 26, 1916.

Application filed January 4, 1916. Serial No. 70,127.

To all whom it may concern:

Be it known that I, JOSEPH PEYSER, a citizen of the United States, and resident of Mount Vernon, in the county of Westchester and State of New York, have invented a new and useful Improvement in Umbrellas or Parasols, of which the following is a specification.

This invention relates to an improvement 10 in umbrellas or parasols, with the object in view of providing an umbrella which is formed and operated without a rib.

Another object is to provide an umbrella in which the cover and its supporting member are formed of a stiff, waterproof material, preferably paper.

Another object is to provide an umbrella in which the cover and its supporting member are so formed that they will be brought, 20 when closed, into interfolded relation, thereby maintaining a perfect folded or creased condition necessary for the successful manipulation of the umbrella.

Another object is to provide a ribless umbrella which will be simple in construction, effective and cheap in the manufacture.

A still further object is to provide certain improvements in the form, construction and arrangement of the several parts, whereby 30 the above mentioned and other objects may be effectively carried out.

A practical embodiment of my invention is represented in the accompanying drawings, in which—

35 Figure 1 represents a side elevation of my improved umbrella or parasol in its closed position, Fig. 2 is an inverted plan of the same, Fig. 3 is a longitudinal central section taken in the plane of the line A—A of Fig.

40 1, Fig. 4 is a horizontal section on an enlarged scale, taken in the plane of the line B—B of Fig. 1, looking in the direction of the arrows, Fig. 5 is a side elevation of the umbrella in its open position, Fig. 6 is a 45 longitudinal central section taken in the plane of the line C—C of Fig. 5, and Fig. 7 is an inverted plan of the same.

The cover of the umbrella, denoted by 1, is formed of a stiff, waterproof material, preferably paper, which is crimped to form 50 alternating radial ridges 2 and furrows 3. This cover is permanently secured to a stick or rod 4 at the point where the ridges 2 and furrows 3 issue, by any well known and 55 approved means, such, for instance, as be-

ing wrapped with cord 5 and glued to the stick 4 at or near the outer end thereof.

The supporting member 7 is also crimped to form alternating ridges 8 and furrows 9. The number of ridges 8 correspond to the 60 ridges 2, likewise the number of furrows 9 correspond to the furrows 3. In the present instance, I have shown sixteen ridges and sixteen furrows in both the cover 1 and the supporting member 7, but I may make 65 the cover and member with more or less ridges and furrows. Thus it will be seen that by making an even number of ridges and furrows in both the cover and the supporting member, they will be caused to interfold when the umbrella is in its closed position, thereby maintaining them in perfect folded or creased condition, which condition is essential for the successful manipulation of the umbrella.

70 The supporting member 7 is secured to the cover 1 with the ridges 8 inverted, by means of tabs 10 carried by the member, which tabs are glued or otherwise fastened to the under side of the inclined walls between the ridges 2 and furrows 3. The supporting member 7 is secured at its center 11, from which the ridges 8 and furrows 9 issue, to a collar 12, by any well known and approved means, such as gluing. This collar 75 12 is adapted to slide freely upon the stick 4.

In order to hold the collar 12 in position at the outer end of the stick 4, I provide a resilient latch 13, one end of which is pinned to the stick at 14 and provided with an incline 15 upon which the collar rides and depresses the latch in its upward movement. After the collar has passed the incline 15, the desired distance, it will register with a notch 16 formed in the latch, which will thereupon spring outwardly, thereby locking the collar in its outer position.

80 A resilient latch 17, similar in construction to the latch 13, is pinned to the stick at 18 and is provided with a notch 19 which is adapted to receive the collar 12 and thereby hold it in its inner position. The latches 13 and 17 are semicircular in cross section 85 so as to straddle the stick 4.

100 To provide for a free swinging movement of the supporting member with respect to the cover 1, each tab is creased at 20 and 21, so that the portion 22, intermediate of the 110

creases, will be free to fold as the supporting member is forced inwardly and outwardly on the stick 4.

In operation; when it is desired to open 5 the umbrella, the latch 13 is pressed inwardly, which movement allows the collar 12 to be forced upwardly, which, in turn, forces the supporting member upwardly and outwardly, thereby pushing the cover, 10 at the points of the tabs, upwardly and outwardly. The collar may be forced upwardly upon the stick 4 until it reaches the resilient latch 13, when it will ride up the incline 15 and depress the latch until it 15 arrives in register with the notch 16, whereupon the latch will be released and spring outwardly, locking the collar member and cover in their outermost position. The umbrella now assumes the position shown in 20 Figs. 5 to 7 inclusive. To close the umbrella, the movements of the several parts are reversed. The latch 13 is depressed by the operator, thereby releasing the collar 12 from the notch 16, which collar may be 25 drawn downwardly, pulling the supporting member and cover with it, until it arrives at the latch 17, which will be depressed by the collar until it arrives at the notch 19. When the collar registers with the notch 30 19, the latch 17 will immediately spring outwardly, thereby locking the collar in the notch, in which position the umbrella will be closed, as shown in Figs. 1 to 4 inclusive. Thus it will be seen that the movement of 35 the collar will control the supporting member and cover, locking the same against any inward or outward movement by the notches 16 and 19 formed in the latches 13 and 17.

40 In the accompanying drawings, the cover is shown as circular in form, but it is not essential that it should be so shaped, as it may be cut to any fanciful configuration.

It is evident that various changes might 45 be made in the form, construction and arrangement of the several parts without departing from the spirit and scope of my invention; hence I do not wish to limit myself strictly to the structure herein shown and 50 described, but

What I claim is:—

1. A ribless umbrella comprising a stick, a radially crimped cover secured thereto, a supporting member hinged directly to said 55 cover, and means for locking said member to the stick for holding the cover in either opened or closed position.

2. A ribless umbrella comprising a stick, a radially crimped cover secured thereto, a

crimped supporting member hinged thereto, 60 and means for locking said member to the stick for holding the cover in either opened or closed position.

3. A ribless umbrella comprising a stick, 65 a radially crimped cover secured thereto, a radially crimped supporting member hinged thereto, and means for locking said member to the stick for holding the cover in either opened or closed position.

4. A ribless umbrella comprising a stick, 70 a cover having radially alternating ridges and furrows secured thereto, a supporting member hinged to said cover, said member having radially alternating ridges and furrows adapted to interfold with aforesaid 75 ridges and furrows when in closed position, and means for locking the supporting member to the stick for holding the cover in an opened position.

5. A ribless umbrella comprising a stick, 80 a cover having radially alternating ridges and furrows secured to said stick, a supporting member hinged to said cover, said member having radially alternating ridges and furrows adapted to interfold with the aforesaid 85 ridges and furrows when in closed position, means for locking the supporting member to the stick in a closed position, and means for locking said member to the stick for holding the cover in an opened position. 90

6. A ribless umbrella comprising a stick, a cover having radially alternating ridges and furrows secured to said stick, a supporting member having tabs secured to said 95 cover, said member being provided with radially alternating ridges and furrows adapted to interfold with the aforesaid ridges and furrows when in closed position, and means for locking the said member to the stick for holding the cover in an opened 100 position.

7. A ribless umbrella comprising a stick, a cover having radially alternating ridges and furrows secured to said stick, a supporting member having tabs secured to said 105 cover, said member being provided with radially alternating ridges and furrows adapted to interfold with the aforesaid ridges and furrows when in closed position, means for locking the supporting member 110 to the stick for holding the cover in a closed position, and means for locking the said member to the stick for holding the cover in an opened position.

In testimony, that I claim the foregoing 115 as my invention, I have signed my name this 31st day of December, 1915.

JOSEPH PEYSER.
